UNITED STATES PATENT OFFICE.

WILLIAM T. SMITH, OF BALTIMORE, MARYLAND.

LUBRICATOR.

SPECIFICATION forming part of Letters Patent No. 340,385, dated April 20, 1886.

Application filed February 11, 1886. Serial No. 191,539. (No model.)

To all whom it may concern:

Be it known that I, WILLIAM T. SMITH, of Baltimore, in the State of Maryland, have invented certain new and useful Improvements 5 in Lubricators; and I do hereby declare the following to be a full, clear, and exact description of the invention, such as will enable others skilled in the art to which it appertains to make and use the same.

10 My invention relates to an improvement in lubricators, and more particularly to that class of lubricators employed in supplying a lubricant in its non-liquid state to journals.

The object of my present invention is to 15 provide a lubricator which shall economize grease, keep the journals constantly lubricated, and which shall be simple and inexpensive in construction.

With these ends in view my invention consists in certain features of construction and 20 combinations of parts, as will be hereinafter described, and pointed out in the claim.

In the accompanying drawings, Figure 1 is 25 a view of the lubricator in position on a journal-box, and Fig. 2 is a view of a modified form adapted for use in connection with carriage or wagon wheel hubs or loose pulleys.

A represents a cylindrical-shaped cup, preferably provided with a rounded base, as 30 shown, and terminating at its lower end in a screw-threaded tap, *a*. An angular-shaped nut-section, *B*, is conveniently formed between the screw-tap *a* and the bottom of the cup for convenience in screwing the cup on and off the journal-box. The interior of the 35 cup *A* is screw-threaded from top to bottom, as shown at *C*, and a plunger, *D*, is provided with a male thread, *d*, on its edge, adapted to register with the thread *C*. The lower face of 40 the plunger *D* is preferably concave, forming a chamber, *E*. The plunger *D* is further provided with a stem, *e*, on its upper side, and a thumb-wheel, *F*, is formed on the stem for conveniently operating the plunger.

45 In operation the cup is filled with a lubricant in non-liquid form—a lubricant composed of paraffine and neat's foot oil, for example—and the plunger *D* is inserted in the top of the cup. One or two turns of the 50 plunger will force the grease out of the

perforation in the tap *a* onto the journal by the compression of the air between the lower face of the plunger and the upper surface of the grease. The grease in the screw-threads will effectually seal the slight opening around the edge of the plunger, between it and the cup, so that there will no air escape, however great the compression may be which is required to force the grease onto the journal. The rotary motion of the journal after the grease has begun to feed will tend to produce a slight vacuum beneath the end of the tap *a*, which will in turn cause the grease to automatically feed in to fill it, and the operation will continue until the air between the upper surface of the grease in the cup and the lower face of the plunger has become so rarefied that it will destroy the effect of the vacuum formed by the rotating journal, when it will be necessary to give the plunger 70 a turn. So perfect and economical is this feed that fast-running machinery will require but one turn of the plunger each day, while line-shafting will require but one turn per week.

In Fig. 2 is shown a form of cup and plunger adapted to be inserted in the hub of a wagon-wheel or loose pulley. The extended stem of the plunger is replaced by a short projection, *e'*, or a depression would answer, by means of 75 which the plunger might be turned either by the thumb and finger or by a suitable key. The cup is also in this construction provided with a screw-cap, *M*, to prevent the mud and dust from filling in the upper end as the 80 plunger descends. The upper end of the cup would be conveniently about flush with the surface of the hub, thus forming no obstacle to the free rotation of the wheel or pulley, and obviating the necessity in the case of wagon-wheels of removing the wheel for greasing.

By means of pipes leading from the lubricator, located at a point within convenient reach of the driver, to the four journals of a street-car, the driver may by a turn of the 95 plunger lubricate the journals while the car is in motion. The lubricator may also be used to lubricate the flanges of car-wheels before turning a curve by pipes leading into the proper position on locomotives and in con- 100

nection with all classes of running-gear where lubricators are employed.

Having fully described my invention, what I claim as new, and desire to secure by Letters Patent, is—

The combination, with an internally screw-threaded cup having a screw-tap for attaching it to a bearing, and having an internal screw-thread extending from top to bottom, of a concave-faced plunger located wholly within the cup, and having a threaded periph-

ery and a reduced operating-stem formed on the upper surface of said plunger integral therewith, substantially as set forth.

In testimony whereof I have signed this 15 specification in the presence of two subscribing witnesses.

WM. T. SMITH.
